UNITED STATES PATENT OFFICE

153,414

DESIGN FOR A DICTATING MACHINE

Emmanuel Berlant, Culver City, Calif., assignor
to Berlant Associates, Los Angeles, Calif., a
partnership

Application November 19, 1948, Serial No. 149,729

Term of patent 14 years

(Cl. D26—14)

To all whom it may concern:

Be it known that I, Emmanuel Berlant, a citizen of the United States, residing at Culver City, in the county of Los Angeles and State of California, have invented a new, original, and ornamental Design for Dictating Machine, of which the following is a specification, reference being had to the accompanying drawing, forming part thereof.

Fig. 1 is a perspective view of a dictating machine showing my new design.

Fig. 2 is a top plan view.

Fig. 3 is a front view in elevation.

The salient features of the design are shown in full lines.

I claim:

The ornamental design for a dictating machine, substantially as shown and described.

EMMANUEL BERLANT.
